UNITED STATES PATENT OFFICE

FRANK G. BAUM, OF SAN FRANCISCO, CALIFORNIA, ASSIGNOR TO WESTINGHOUSE ELECTRIC AND MANUFACTURING COMPANY, A CORPORATION OF PENNSYLVANIA

HIGH-VOLTAGE INSULATOR

Application filed December 3, 1921. Serial No. 519,592.

This invention relates to the insulation of conductors for high voltage power transmission lines, and particularly under outdoor weather conditions.

5 In insulating devices for such lines, a dry surface provides a greater resistance than a wet surface, and therefore has a greater insulating effect. If a surface between two points differing greatly in potential is divided 10 into wet and dry sections, the electrical stress will be largely concentrated upon the dry sections with the result that the air along the dry sections breaks down successively until an arc occurs, which because of its heat is frequently 15 disastrous to the insulators that are usually of porcelain. The ideal insulator is therefore one with a uniformly wet surface or one with a maximum dry leakage surface.

With insulator units for insulating high 20 voltage conductors, it has been found in practice that very high electrical stresses are set up adjacent the metallic pins or connectors upon the under faces of the insulator bodies and these stresses frequently form coronas 25 which extend radially outward across the insulator surface. That is, the corona adjacent the metallic connector breaks down the air and this breakdown of the air lowers the resistance and transfers the electrical stress 30 further out and causes a further breaking down of the air with the result that the corona creeps outwardly along the under surface. Corona, because of the fact that in the presence of moisture it forms acids, is a source of 35 danger when it can spread in this manner. The small circular corrugations, commonly placed upon the under surfaces of insulators, fail to effectively prevent the spread of the corona, it having been found in practice that 40 the corona will spread along the surface to the nearest corrugation and then jump from corrugation to corrugation across the surface.

The purpose of this invention is to provide 45 an insulating device for high voltage conductors with which the outward spread of corona is limited or prevented, which has sufficient dry surface under ordinary outdoor weather conditions to prevent a material breaking down of the insulating effect, and which pre-

vents the concentration of the potential across small dry surfaces when subjected to driving rain. A further object is to provide an insulating device in which a maximum possible cleansing action of rains upon the surfaces 55 will be obtained, and which will be strong and durable in construction and have a maximum insulating effect. Other objects and advantages will be apparent from the following detailed description of embodiments of the invention and the novel features will be particularly pointed out in claims.

In the practice of the invention, I propose to limit or prevent the formation and movement of corona on insulators by providing a 60 corona shield upon the under surface of each unit. This shield is preferably in the nature of a porcelain skirt integral with the porcelain body of the unit at a point closely adjacent the connector, and extending downwardly a predetermined distance and outwardly until its inner surface has a length at least approximately equal to the distance from said point to a metallic enlargement on the connector below the insulator body, which in 65 the cap and pin type, may be the cap of the next lower unit. I also contemplate constructing these units of different diameters, so that when arranged in the string with the larger units interspersed between the smaller 70 units, the larger units will overhang and at least partially protect the smaller units against light rains and against drip from the units above it. I may also provide insulator units with a plurality of transversely disposed rain shedding flanges having their upper and under surfaces inclined upwardly toward the axis and the inner edges of the surfaces which face one another connected by 75 easy curves without sudden or sharp changes 80 in direction, so that rain striking an upper surface will be deflected against the under surface of the flange immediately above it and at least partially wash the same. The shield 85 may be considered as a flange and its upper surface is connected at its inner edge with the under surface of the flange immediately above it by an easy curve to facilitate cleansing of the said under surface under driving rains. The flanges are also preferably made 90 95 100

of different diameters so that a portion of them will overhang the others and protect them against ordinary rains and against drip from those above it.

5 In the accompanying drawings—

Figure 1 is a sectional elevation of a portion of an insulator string with the insulator units constructed in accordance with my invention;

10 Figure 2 is a sectional elevation of a portion of a string with a slightly modified insulator unit;

15 Figure 3 is a sectional elevation of an insulator bushing constructed in accordance with my invention; and

20 Figure 4 is a sectional elevation of a slightly modified type of insulator bushing.

In a usual insulator unit of the cap and pin type, the body of insulating material extends like a flange from a central or boss portion. In some forms the under surface inclines directly from the periphery to the pin connector, and in others it may have depending circular ribs. With units of this type it 25 has been found in practice that high electrical stresses are set up at points on the under surface immediately surrounding the connecting pin. These stresses form corona on the under surface which tend to extend 30 radially outward to the periphery of the unit. That is, the high electrical stress surrounding the pin tends to break down the air immediately adjacent thereto, and the breakdown lowers the resistance so that the high 35 electrical stress is extended towards the periphery of the unit. A further section of the air is then broken down so that the air will be broken down successively and permit of the extension of the corona to the periphery 40 of the unit. The ribs do not limit the movement of the corona, and it has been found by test that the corona tends to extend along the under surface of the porcelain body until it reaches the tip of the rib first encountered, 45 after which it jumps successively to the tips of the other ribs and then to the periphery of the insulator unit. In the presence of moisture the formation of acids by the corona is a source of danger when the corona can 50 spread over the surface in this manner.

In Figures 1 and 2 I have shown an insulating device in which the formation of corona is either prevented or its spread across the under surface of the unit limited. The 55 units, which by way of illustration are shown as of the cap and pin type, comprise a body 1 of insulating material, such as of porcelain, having a central boss 2 over which is secured a metallic cap 3 for the suspension of this 60 unit from the next higher unit, or from the support. A connector pin 4 is secured in a recess 5 centrally beneath the cap 3 in a suitable manner such as by cement, and serves to support therefrom the next lower unit or the 65 conductor through its pivoted connection

with the ears 6 of the cap of said lower unit or with the conductors. The insulating body is provided with a transversely disposed flange 7, the surfaces of which both extend outwardly and downwardly, so that the upper surface thereof will shed the rain. The body 1 is also provided with a second flange in the nature of a corona shield 8 which extends downwardly from the under surface thereof at a point adjacent the connector pin. This shield may conveniently comprise an integral skirt which extends obliquely away from the connector pin at its point of connection with the porcelain body, with its inner surface of a length at least approximately equal to the distance of the metallic cap or enlargement in the connector from said point. The shield constructed in this manner will have a surface-creepage rupture strength between the points *e* and *f* at least equal to the rupture strength of the dielectric at the arcing zone, indicated as disposed along the line *g*, between the insulator and the lower metallic parts under wet conditions, and, at the same time, permits a string of similar insulator units to be assembled in a string of substantially minimum length. Since the potential from the connector to the point *f* is limited in this manner I may give the skirt an inclination to the pin such that it will prevent corona, but if any corona does form, it will build down successively along the under side of the skirt only to an extent in which its potential difference from the point *e* equals that across the air at the distance *g* between the metallic connector and the skirt. Practical tests have indicated that such a skirt effectively limits the action of the corona and prevents a breakdown of the insulator, especially under wet conditions.

The insulator units may be made of different diameters so that units of greater diameter than the others may be interspersed along the string whereby the smaller units may be shielded from ordinary rains and from drippage from the units above them. At the same time the driving rains may engage the upper surfaces of the smaller units, as well as the larger units and cleanse them from accumulations of dust, etc. Each under surface except the lowermost one is cleansed by the driving rain deflected from the upper surface immediately below it. This deflection of driving rain is facilitated by connecting the inner edges of the under surface of the rain shedding flange and the upper surface of the shield flange by an easy or free curve 8^a, i. e., a curve without sharp or sudden changes in its rate of change of curvature, so that a driving rain engaging with the upper or outer surface of the shield will not only spatter upon the upper surface but will also be deflected upwardly along the connecting curve and then outwardly across the under surface of the flange.

In Figure 2 the insulating body 9 of a unit is provided with a plurality of transversely disposed rain shedding flanges 10 which are progressively smaller in diameter from the top to the bottom, and the lowermost flange 11 extends as a skirt to form a corona shield as in the embodiment of Figure 1. The upper and lower surfaces of each of these flanges are inclined upwardly towards the axis of the insulating body and the lower surface of each flange is connected at its inner edge with the inner edge of the upper surface of the flange immediately below it by a free or easy curve 12, for deflecting driving rains to cleanse the under surfaces of the flanges, in a manner similar to that effected by the curve 8^a (Figure 1). The under surface of the skirt or corona shield 11 extends obliquely and upwardly toward the connector pin 13.

In Figure 3 I have illustrated the application of the invention to bushings for use on transformers, switches, and the like, for the insulation of high voltage conductors. The body 14 of each unit is of suitable insulating material, such as of porcelain, and is provided with flanges 15 similar to the flanges 10 of the units shown in Figure 2, except that the corona shield may be omitted. The upper and lower surfaces of the flanges which face one another are connected by easy curves 12^a similar to the curves 8^a and 12 of the structures shown in Figures 2 and 3. Each unit is provided with an axial boss 16 at one end and a recess 17 at the other end adapted to receive the boss 16 of another unit disposed in end to end relation therewith. These units are secured together end to end in a suitable manner, such as by cement 18 and the aligned central longitudinal apertures 19 are lined with insulating sleeves of porcelain or other suitable material 20.

In Figure 4 a slightly modified type of bushing is illustrated in which the peripheral flanges 21 and 22 are alternately of greater and less diameter so that each flange of larger diameter shields the smaller flange immediately below it from ordinary rains. The under surface of each of these flanges is connected with the upper surface of the flange immediately beneath it by a free curve similar to the curves 8^a and 12 of Figures 1 and 2 and for the same purpose.

In the insulating units of the types shown, the flanges which are overhung by those above them will be protected against ordinary rains so that a very large dry leakage surface will be available on each unit to provide the necessary resistance. Driving rains will engage the lower or outer portions of the flanges of smaller diameter and because of the free curves connecting the upper surfaces of these flanges with the under surfaces of the flanges immediately above them, the driving rain engaging with the upper sur-

faces of the flanges will be deflected and directed along the free curves to a maximum extent and thereby cause a cleaning of the maximum possible area of the surface between two flanges. The upward and inward inclination of the under surfaces of the flanges prevents the passage of the rain inwardly along the same by capillary action, so that the under surface of each flange will remain free from running moisture, except during driving rains in which case approximately the entire leakage surface will be wet. The leakage surface provided therefore closely approaches the ideal condition of a uniformly moist surface or a surface having a maximum possible dry area.

It will be obvious that various changes in the details and arrangements herein described and illustrated may be made by those skilled in the art within the principle and scope of the invention.

I claim:

1. An insulator comprising an insulating member having a plurality of laterally projecting portions having downwardly-and-outwardly-sloping upper and under surfaces, the under surface of one of said portions and the upper surface of the next lower thereof being spaced and formed relative to each other and joined by a surface of rounded contour in accordance with the force of driving rain to cause the rain to travel in a stream therealong from said upper surface to said under surface.

2. An insulator comprising an insulating member having a plurality of superposed laterally-and-outwardly projecting annular flanges having downwardly-and-outwardly-sloping upper and under surfaces, the under surface of one of said flanges and the upper surface of the next lower flange being spaced and formed relative to each other and joined by a surface of rounded contour in accordance with the force of driving rain to cause the rain to travel in a stream therealong from said upper surface to said under surface, the arrangement of surfaces tending to substantially uniformly wet the entire outer surface of the insulator during a driving rain.

3. A high-voltage insulator comprising upper and lower terminal members, and an insulating member having a plurality of outer flanges having downwardly-and-outwardly-sloping upper and under surfaces, the under surface of one of said flanges and the upper surface of the next lower thereof being spaced and formed relative to each other and joined by a surface of rounded contour in accordance with the force of driving rain to cause the rain to travel in a stream therealong from said upper surface to said under surface and the lowermost of said flanges having an under surface providing a creepage rupture strength therealong at least equal to the rupture strength of the

air across the shortest arcing zone between the lower terminal and the insulating member under wet conditions.

4. A high-voltage insulator comprising upper and lower terminal members, and an insulating member having an upper rain-shedding flange and a lower corona-shielding flange constituting homogeneous parts thereof, the under surface of said rain-shedding flange and the upper surface of said corona-shielding flange being spaced and formed relative to each other and joined by a surface of rounded contour in accordance with the force of driving rain to cause the rain to travel in a stream therealong from said upper surface to said under surface and the under surface of said corona-shielding flange having a creepage rupture strength therealong at least equal to the rupture strength of the air across the shortest arcing zone between the lower terminal and said corona-shielding flange under wet conditions.

In witness whereof, I hereunto subscribe my signature.
